A. B. CAMERON.
PANEL.

No. 20,362.

Patented Dec. 2, 1890.

UNITED STATES PATENT OFFICE.

ALLAN B. CAMERON, OF WILLIAMSPORT, PENNSYLVANIA.

DESIGN FOR A PANEL.

SPECIFICATION forming part of Design No. 20,362, dated December 2, 1890.

Application filed November 12, 1889. Serial No. 330,084. Term of patent 14 years.

To all whom it may concern:

Be it known that I, ALLAN B. CAMERON, of Williamsport, Lycoming county, Pennsylvania, have invented and produced a new and 5 original Design for Panels, of which the following is a specification, reference being had to the accompanying photograph, forming part hereof.

My design relates to a panel having upon 10 its surface the following ornamental configuration: Upon the surface of the panel appears a circular elevation A. From the center of said circular elevation channels C radiate to the

periphery of said elevation. The number of said channels is immaterial. Upon the sides 15 of said channels and around the periphery of the circular elevation A appears steps or ledges.

I claim as my invention—

The design for an ornamental panel, substantially as herein shown and described.

ALLAN B. CAMERON.
